UNITED STATES PATENT OFFICE

FERNAND TOURTOIS, OF NEW YORK, N. Y., ASSIGNOR TO COTY, INC., OF WILMINGTON,
DELAWARE, A CORPORATION OF DELAWARE

COSMETIC CONTAINER

Application filed April 6, 1931. Serial No. 527,900.

This invention relates to improvements in containers for cosmetics and more particularly to holders for compacts, lipsticks, rouges, and similar articles.

5 A particular object of this invention is the provision of a hermetically sealed holder for toilet powder or rouges in compact form and holders for similar cosmetics, in which the exact shade of the cosmetic contained within 10 the holder may be determined without opening the article and exposing the compact to view.

Further objects of the invention will be apparent from the specification and drawing 15 in which

Fig. 1 is a perspective of a form of my improved holder for a rouge compact viewed from the bottom.

Fig. 2 is an elevational section.

20 Fig. 3 is a perspective view of the paper insert whose use will be hereinafter described. 10 indicates the bottom of the box or holder, 11 the cover, 12 the rouge compact contained in the holder. 13 is a slot or opening 25 in the bottom wall of the holder or container which, in this particular embodiment, is shown to be oval in shape but may be varied according to the size and nature of the article.

14 is an insert covering the bottom of the 30 holder preferably made of paper although it can also be made of metal foil or other material. The outer surface of the insert 14 is colored to correspond exactly with the shade of the rouge compact 12, and the upper 35 surface of the insert 14 is securely glued to the bottom of the holder for the rouge compact. In view of the fact that the color of the bottom of the insert 14 exactly matches the color or the shade of the cosmetic contained in the holder, an observer or possible 40 purchaser can readily tell the shade of the cosmetic without raising the cover 11 and thus subjecting the cosmetic to air, dust, or other causes of possible deterioration. In 45 placing the insert 14 in the bottom, care should be taken so that same will fit the bottom tightly so as not to permit the entrance of any dust into the holder.

It is apparent that further changes may be 50 made in the form of the slot, in the form of

the cosmetic, and in the manner in which the insert 14 is held in the bottom of the holder, without departing from the spirit of my invention.

What I claim is:

1. In combination a container of the character described, comprising a covered casing and a cosmetic compact therein, containing colored material, a surface thereof which is exposed when said casing is in an uncovered condition, to permit a partial or complete removal of said material through the exposure of said surface, an insert being colored to correspond to the shade of the material and located below the surface of the material and between the compact and bottom wall of the casing and an opening in the bottom wall of the casing to disclose the color of said insert. 55

2. In combination a container of the character described, comprising a covered casing 70 and a cosmetic compact therein containing colored material, a surface thereof which is exposed when said casing is in an uncovered condition to permit a partial or complete removal of said material through the exposure of said surface, an insert being colored to correspond to the shade of the material and located outside the walls confining the material within the box and between the compact and outer wall of the casing, and an opening 75 in the wall of the casing to disclose the color of said insert. 80

In testimony whereof I affix my signature.

FERNAND TOURTOIS.
